FIG. 2

INVENTOR

INVENTOR

UNITED STATES PATENT OFFICE.

VINCENT H. FRANCIS, OF DRUMRIGHT, OKLAHOMA, ASSIGNOR TO FRICK-REID SUPPLY COMPANY, OF PITTSBURGH, PENNSYLVANIA, A CORPORATION OF PENNSYLVANIA.

PUMP.

1,284,641.

Specification of Letters Patent. Patented Nov. 12, 1918.

Application filed June 23, 1917. Serial No. 176,555.

To all whom it may concern:

Be it known that I, VINCENT H. FRANCIS, a citizen of the United States, and resident of Drumright, in the county of Creek and State of Oklahoma, have invented a new and useful Improvement in Pumps; and I do hereby declare the following to be a full, clear, and exact description thereof.

My invention relates to pumps for oil or like wells, and is devised particularly though not exclusively as a pump for deep oil wells adapted to be operated by a wire rope or pump rods.

Heretofore the operation of pumping deep wells in which rods or wire rope is employed for reciprocation of the pump-piston, the volume of flow, or the capacity of the pump is limited to the rapidity with which the pump-piston can be reciprocated by the wire rope or rods. Difficulties obtain by reason of the flexibility of the pumping connection between the pump beam and the pump-piston, permitting the pump-piston to be retarded on the down-stroke by compression of the fluid in the pump chamber, between the bottom or standing valve and the working valve or piston. The opening in the check-valve of the piston being only a small opening as compared with the piston area, permits the valve to settle down only as fluid is displaced through this opening. The slow settling of the valve on the down-stroke, causes slack in the pumping rods or wire rope and irregularity of the pumping-stroke of the piston, with resultant lessened capacity per pumping minute. Also, by reason of slack in the rods or wire rope the pump connections are subjected to severe strains when the pumping-beam takes up the slack, often resulting in breakage of the connections, etc.

Water and gas pressure in the working-barrel also act in a like manner to retard the downward movement of the piston, and besides, the gas creates a pressure on the inlet or standing valve which restricts or totally obstructs flow of fluid through this valve.

The primary object of my invention is to provide a pump adapted to be operated by rods or wire rope which is so constructed as to permit full length strokes in regular or substantially regular time intervals in each direction, and which may be operated at any desired degree of rapidity, and thereby provide for greater capacity per pumping hour.

A further object is to provide means which prevent obstructive gas pressure in the working-chamber of the pump.

The invention consists in the novel construction, as hereinafter described and 60 claimed.

Figure 1 of the drawing is a longitudinal sectional view of my invention; and Fig. 2 is an enlarged longitudinal section of one of the valves employed.

The numeral 2 indicates a portion of the well-tubing to which my improved pump is attached, the location of the pump with reference to its position in the well being the same as with the standard arrangement for 70 pumping. The pump comprises the working-barrel 3 which may be the standard working-barrel of a regular oil-well pump, with anchor-tubing and strainer 4, lower or standing-valve 5, and traveling valve or piston 6. The traveling valve is connected to the pumping-cable (not shown) by the valve-rod 7. The type of check-valves within the barrel may be of any of the well-known types of check-valves used in pumps 80 now employed in work of this general character. I prefer, however, to employ a double check-valve for the standing valve, so as to lessen the liability of leakage in the pump-chamber due to the sand in the valve. It 85 has been found that with a double-seated valve the lower seat of the valve is exposed less to the action of the sand than the upper seat, and for this reason there is an advantage in the employment of a double valve. 90 Also this valve is made with an elongated stem 5^a, the purpose of which will herein-after appear.

All of the above structure so far described functions in a manner precisely the same as 95 with the standard pump as now employed. The working-barrel in the present invention is provided with means for by-passing a portion of the fluid from the pump-chamber to a point above the uppermost position of the 100 traveling valve on the down-stroke of the valve, and for venting the chamber of obstructive gases, permitting the free downward movement of the valve.

The working barrel in this instance communicates by a port 10 with a by-pass connection 11 which communicates with the anchor-tube below the strainer section. Port 10 is located preferably just above the standing valve of the pump chamber and 110

the stem 5^a of the valve projects upward far enough to prevent closure of this port by the pump piston in case of slippage or stretching of the pump cable. The by-pass 11 is 5 provided with a check valve, and preferably two of such check-valves 12 are employed, the double arrangement being for the same purpose as the double-valve of the pump-barrel, and these valves also seat down- 10 wardly. The structural arrangement of the by-pass includes a slip-joint connection 13 adapted to permit of adjustment of the several sections and to facilitate the assembling of the connection on the pump-barrel. The 15 by-pass so arranged provides a greater intake area to supply the pump-chamber with fluid on the up-stroke of the piston, and by reason of the double connection to the pump-chamber insures a constant supply of fluid 20 to the chamber in case of failure of one of the valve connections to admit fluid to the chamber.

A by-pass 14, preferably a continuation of the by-pass 11 connects to the pump-chamber at port 10, and terminates in the pump-tubing, or working-barrel at a point 15 above the uppermost position of the traveling valve. This section of the by-pass also is provided with a pair of downwardly seating 30 check-valves 16 and a slip-joint connection 17, which are in structure similar to valves 12 and joint 13. The function of this section of the by-pass is to convey fluid from the pump-chamber on the downward stroke 35 of the traveling valve, from between the valves of said chamber to a point in the pump-tubing above the traveling valve. The enlarged detail Fig. 2 of the drawing shows the preferred construction of the check-valve 40 and slip-joints of both sections of the by-pass. These valves are especially designed for the particular arrangement shown and include structure forming the subject of a 45 separate application for Letters Patent filed by me of even date herewith, Serial No. 176,559.

Other forms of check-valves and by pass pipe structure may be used which function in a similar manner, and it is to be under- 50 stood I do not limit my invention to the precise arrangement of the check-valves and by pass as shown. The by-pass may be arranged in two separate sections and have separate and distinct connections with the 55 pump-chamber as shown and described in an application filed of even date herewith. I prefer, however, to employ the structure as illustrated, as in this manner the invention may readily be applied to the regular 60 pumping outfit, the attenuated form of check-valve permitting close positioning of the by-pass pipe to a standard working-barrel which makes a compact structure which may readily be inserted through the 65 well-casing.

In the operation of my improved pump, upward movement of the working valve or piston 6 acts to draw fluid into the pump-chamber through standing valve 5 and through the by-pass 11 and port 10 and 70 move up the column of fluid above the working valve. Downward movement of the valve acts to displace the fluid so drawn in, by forcing the fluid through the check-valve of the piston as in the usual manner, and 75 through port 10, and by-pass 14 into the tubing above the traveling-valve. The port 10 and the opening of the valve in the piston 6 provide openings for the escape of the fluid of the chamber when under compres- 80 sion of the downwardly traveling valve, the combined area of these openings permitting of rapid displacement of the fluid. It will be seen that by by-passing a portion of the fluid in this manner, the resistance in the 85 pump-chamber by fluid to the descending piston is greatly relieved, and at the same time the port 10 allows gas in the pump-chamber to escape, thus relieving the piston entirely of burden from compression and 90 permitting more rapid reciprocation of the piston, resulting in increased flow or capacity of the pump per pumping hour. Furthermore, by reason of the by-pass connections from the strainer to the tubing 95 above the traveling valve, when fluid is standing in the casing above the working barrel, head pressure in the casing will force the fluid up through the by-pass to its own level in the tubing thereby greatly increas- 100 ing the pumping efficiency.

It will be seen from the foregoing description of the structure and its operation that I have provided a pump of high pumping efficiency, which is simple and compact in 105 structure and which may readily be applied to the standard pumping outfits.

What I claim is:

1. In a pump for oil or other deep wells, the combination with a working-barrel having a standing valve for admission of fluid at the lower end thereof, of a single piston operable in the barrel for suction of the fluid to and for expulsion of the fluid from the barrel in pumping operation, 110 said piston controlling said valve, and an auxiliary fluid passage having independent communication with the source of fluid supply and communicating with the barrel at opposite sides of the piston. 115

2. In a pump for oil or other deep wells, the combination with a working barrel having a standing valve for admission of fluid at the end thereof, of a single piston operable in the barrel for suction of the fluid to, 120 and for expulsion of the fluid from the barrel in pumping operation, said piston controlling said valve, an auxiliary fluid passage having independent communication with the source of fluid supply and communi- 125 130

cating with the barrel at opposite sides of the piston, and a valve in said auxiliary passage influenced by the movement of said piston for controlling flow of fluid to the barrel.

5 barrel.

3. In a pump for oil or other deep wells, the combination with a working barrel having a standing valve for admission of fluid at the end thereof, of a single piston oper-
10 able in the barrel for suction of the fluid to, and for expulsion of the fluid from the barrel in pumping operation, said piston controlling said valve, an auxiliary fluid passage having independent communication
15 with the source of fluid supply and communicating with the barrel at a point between the standing valve and the piston, and means for by-passing fluid from the barrel around the piston to its opposite side.

20 4. In a pump for oil or other deep wells, the combination with a working barrel having a standing valve for admission of fluid at the end thereof, of a single piston oper-
25 able in the barrel for suction of the fluid from the barrel in pumping operation, said piston controlling said valve, an auxiliary fluid passage having independent communication with the barrel at a point between the pis-
30 ton and the standing valve, a valve in said passage influenced by said piston for controlling the flow of fluid through said pas-
35 sage, and a passage for by-passing fluid around the piston having a permanently
open port communicating with the barrel between the piston and the standing valve.

5. In a pump for oil or other deep well the combination with a working barrel having a standing valve for admission of fluid
40 at the end thereof, of a single piston oper-
able in the barrel for suction of the fluid to and for expulsion of the fluid from the barrel in pumping operation, said piston controlling said valve, an auxiliary fluid pa-
45 sage having independent communication with the source of fluid supply and com-
municating by an inlet port to the barrel at a point between the piston and the stand-
ing valve, and means for limiting the down-
50 ward movement of the piston to a point above the inlet port of said auxiliary pa-
sage.

6. In a pump for oil or other deep wells, the combination with a working barrel having a standing valve for admission of fluid at the end thereof, of a single piston operable in the barrel for suction of the fluid to, and for expulsion of the fluid from the

barrel in pumping operation, said piston controlling said valve, an auxiliary fluid passage having independent communication with the source of fluid supply and communicating by an inlet port to the barrel at a point between the piston and the standing valve, and means carried by the standing valve for limiting the downward movement of the piston to a point above the inlet port of said auxiliary passage.

7. A pump for oil or other deep wells comprising a working barrel and its piston, a standing valve in the lower end of the barrel for admission of fluid, and a separate fluid admission passage having independent communication with the source of fluid supply and communicating with the barrel at opposite sides of the piston. 75

8. A pump for oil or other deep wells, comprising a working barrel and its piston, a standing valve in the lower end of the barrel for admission of fluid, and a separate fluid admission passage having independent communication with the source of fluid supply and communicating with the barrel above the piston and having an admission port to the barrel at a point between the piston and the standing valve. 85

9. In a pump for oil or other deep wells, the combination with a working barrel having a standing valve and including the anchor tubing, of a fluid by-pass having independent communication with the anchor tubing beneath the standing valve and communicating with the barrel between the standing valve and the piston, and means for by-passing fluid from the barrel around the piston from beneath the piston. 95

10. In a pump for oil or other deep wells, the combination with a working-barrel and its piston and having a standing valve for admission of fluid, of a separate fluid admission passage having independent communication with the source of fluid supply and communicating with the barrel between the piston and the standing valve, a downwardly seating check-valve in said passage, a passage for by-passing fluid around the piston, and a valve in said second passage for controlling the flow of fluid therethrough. 100

In testimony whereof, I the said VINCENT 110
H. FRANCIS, have hereunto set my hand.

VINCENT H. FRANCIS.
